UNITED STATES PATENT OFFICE.

ELI N. BALDWIN, JR., OF STRATFORD, CONNECTICUT.

CONCEALED HINGE.

1,078,237.

Specification of Letters Patent. Patented Nov. 11, 1913.

Application filed November 21, 1912. Serial No. 732,669.

To all whom it may concern:

Be it known that I, ELI N. BALDWIN, Jr., a citizen of the United States, residing at Stratford, county of Fairfield, State of Connecticut, have invented an Improvement in Concealed Hinges, of which the following is a specification.

This invention relates to the class of concealed hinges illustrated and described in my pending application Serial Number 714,551, filed August 12, 1912, in which the hinge is so constructed as to be wholly concealed in the closed position, lies flush with the surface of the jamb in the open position and positively retains the door out of contact with an automobile or coach body in the open position, and my present invention has for its object to provide a hinge of this character disclosing no opening into the jamb in the open position, such an opening having been unavoidable in every hinge heretofore produced. This I accomplish by providing an arc-shaped carrying arm for the door, adapted to swing under an outer plate covering the face of the jamb, which passes through a slot between the base plate of the jamb member and said outer plate, which slot is always filled by the carrying arm. In other words, the carrying arm passes into and out of the jamb pocket at the side of the pocket and the side of the jamb instead of through the face of the jamb.

With this end in view I have devised the novel concealed hinge of which the following description in connection with the accompanying drawing is a specification, reference characters being used to indicate the several parts.

Figure 1 is a horizontal section on the line 1—1 in Fig. 3, looking in the direction of the arrows, the door being in the closed position; Fig. 2 a similar view showing the hinge in plan and the door in the open position; Fig. 3 a view partly in section on the line 3—3 in Fig. 1, looking in the direction of the arrows, showing the hinge in elevation and partly broken away; Fig. 4 a section on the line 4—4 in Fig. 2 looking in the direction of the arrows, the hinge being in elevation in the open position; Fig. 5 a section on the line 5—5 in Figs. 1 and 3, looking in the direction of the arrows, showing the face of the jamb, with the hinge in the closed position, and Fig. 6 is a section on the line indicated by 6 in Fig. 2, looking

in the direction of the arrow, the jamb member being in elevation.

10 denotes the door member of the hinge as a whole, 11 the jamb member, 12 a door, 13 a jamb and 25 a pocket in the jamb into which the jamb member is recessed. The jamb member comprises a base plate 14 which for convenience I will describe as lying in the vertical plane, attaching flanges 15 which lie in the vertical plane at right angles to the plane of the base plate and side plates 16 which lie in the horizontal plane and connect the attaching flanges to the base plate. The door member comprises 17 an attaching plate 17, an arc-shaped carrying arm 18 connected thereto and an attaching arm 19 formed integral with the carrying arm. The base plate and the attaching arm are provided with corresponding hinge eyes 20 through which a pin 21 passes in the usual manner. It should be noted that the design of the two members of the hinge is such that each member may be formed integral from sheet metal and that the attaching arm and the carrying arm of the door member are made relatively wide, which gives them great strength and enables them to carry any amount of weight that can be placed upon them under the ordinary conditions of use. In the closed position the carrying arm swings into the pocket between the side plates of the jamb member. Heretofore, so far as I am aware, in every hinge of this character the carrying arm has passed in and out, in swinging to the closed and open positions, through a large and unsightly opening in the face of the jamb, which it was impossible to cover. In my present hinge the door member is so designed as to enable me to cover the opening in the face of the jamb, between the attaching flanges 15 of the jamb member, by means of an outer plate 22 secured to the jamb by the screws 23 which secure the jamb member. The hinge eyes, the carrying arm and the attaching arm are so laid out relatively to each other as to permit the carrying arm to be curved in an arc of a circle of which the hinge pin is the center and to swing under the outer plate and through a slot 24 in the base plate of the door member, that is at the side of the jamb member and the jamb and wholly within the face line instead of through the face of the jamb. The attaching arm lies at a more or less acute angle to the carrying arm and the

latter at a more or less acute angle to attaching plate 17 which is secured to the door. In the closed position of the door, as in Fig. 1, the outer plate will lie in the angle between the carrying plate and the attaching plate. The door is shown as provided with a rearward extension 26 which covers the slot in the closed position. In Fig. 4 the ends of the outer plate are shown as made longer than the jamb member and closed about the attaching flanges, to retain said plate in engagement with the member.

Having thus described my invention I claim:

- 15 1. A hinge of the character described consisting of a jamb member having a base plate and a door member comprising a carrying arm passing through the base plate and adapted to swing wholly within the face line of the jamb member.
- 20 2. A hinge of the character described consisting of a jamb member having a base plate and a door member comprising an attaching plate, a carrying arm, and an attaching arm pivoted to the base plate, said carrying arm passing through the jamb member wholly within the face line of said member.
- 25 3. A hinge of the character described con-

sisting of a jamb member having a base plate and a door member comprising an attaching plate, a carrying arm, an attaching arm pivoted to the base plate, said carrying arm passing through the jamb member wholly within the face line of the jamb member, and an outer plate adapted to cover the jamb member.

4. A hinge of the character described comprising a jamb member having a base plate with a slot, and a door member comprising an arc-shaped carrying arm lying in said slot and adapted to swing wholly within the face line of the jamb member and an attaching arm pivoted to the jamb member.

5. A hinge of the character described comprising a jamb member provided with a slot, a door member comprising an arc-shaped carrying arm lying in said slot and an attaching arm pivoted to the jamb member, and a plate covering the face of the jamb member under which the carrying arm moves.

In testimony whereof I affix my signature in presence of two witnesses.

ELI N. BALDWIN, Jr.
